UNITED STATES PATENT OFFICE.

JOHN C. DUEBER, OF CANTON, OHIO.

DESIGN FOR A WATCHCASE-LID.

SPECIFICATION forming part of Design No. 25,260, dated March 24, 1896.

Application filed February 26, 1896. Serial No. 580,918. Term of patent 3½ years.

To all whom it may concern:

Be it known that I, JOHN C. DUEBER, a citizen of the United States, and a resident of Canton, county of Stark, State of Ohio, have invented and produced a new and useful Design for Watchcase-Lids, of which the following is a full, clear, and exact description, reference being had to the accompanying drawing, making part of this specification.

10 The design relates to the ornamentation of watch lids or backs; and it consists of the configuration shown in the accompanying drawing, wherein the design is shown in side elevation.

15 The object of the design is to ornament the lid or back of a watchcase by the representation thereon of a bicycle-wheel and other parts of a bicycle.

The leading features of the design comprise the representation of the inflated tire A, the 20 rim B, spokes C, handle-bar D, seat E, the daisy-blossoms F, and the representation of bird-wings G central to the lid, signifying flight.

What I claim is—

25 The design for watchcase-lids, substantially as shown and described.

In testimony whereof I have hereunto set my hand this 12th day of February, A. D. 1896.

JOHN C. DUEBER.
